CIGAR

Application filed May 11, 1931. Serial No. 536,359.

My present invention relates generally to cigars, and has particular reference to an improved construction of blunt-end cigars.

While the quality and calibre of a cigar is dependent almost entirely upon the type and origin of tobacco which enters into its construction, the enjoyment of a cigar by the average smoker is readily influenced and often impaired by totally extraneous factors, as, for example, by the freshness of the cigar, the compactness with which it is rolled, etc. Accordingly, there is a popular misconception that cigars of long filler are of a better quality than those having a so-called short filler, i. e., one composed of relatively short shreds and pieces of tobacco. This misconception is due in a large measure to the fact that during the smoking of a short filler cigar, pieces of the filler are apt to work loose and not only impair the strength and firmness of the cigar at the smoking end, but also to annoy the smoker by escaping outwardly through this end. As a matter of fact, however, a short filler cigar of relatively good tobacco, such as Cuban tobacco, may actually be superior in quality to a long filler cigar constructed of relatively inferior tobaccos, such as many of the domestic brands.

It is a general object of my present invention to provide a cigar construction which is of improved strength and compactness and which retains its shape and firm character even under the most severe conditions, so that, when the invention is applied to a short filler cigar of high quality tobacco, the smoker may be enabled fully to enjoy and appreciate the true quality of the cigar, without being adversely influenced by weakness of structure. Although, in many respects, my invention is equally applicable to cigars of long filler, it is of particular advantage and utility in connection with short filler cigars. With respect to such cigars, it is a more particular object of my invention to provide a construction which compactly retains the filler in position under all conditions, greatly minimizing, if not entirely preventing, any annoyance to the smoker which might be due to loosening of the filler and consequent es-

cape of shreds or pieces of tobacco through the smoking end of the cigar.

It is a more particular object of my invention to provide a cigar construction which retains its firmness and shape even after it becomes dried. The undesirable drying of cigars is a problem constantly confronting the cigar manufacturer since the initial moisture content is limited to an amount which will not result in subsequent mildew. It is especially desirable to maintain the strength and staunchness of a short filler cigar because a drying out of such a cigar results almost immediately in a loosening of the filler particles.

The problems of cigar construction and manufacture, hereinbefore illustratively mentioned, are especially difficult to overcome in blunt-end cigars wherein the body of the cigar is substantially cylindrical and untapered and wherein the wrapper has a portion which completely envelops one of the ends of the cylinder. If a cigar of this character dries unduly, the wrapper at the smoking end is likely to crack and loosen the entire construction, and this is likely to occur not only when the cigar is manipulated but even under the pressure conditions which obtain while the cigar is closely packed with others within a box. Where the filler is a short filler, undesired cracking of this character is obviously doubly annoying and likely to completely destroy the smoker's enjoyment of the cigar.

One of the features of my present invention lies in constructing a blunt-end cigar in a manner whereby such cracking of the wrapper is prevented and wherein the filler, especially adjacent to the smoking end of the cigar, is under all conditions snugly and compactly retained in proper position.

A more particular feature of my invention lies in providing a cylindrical body of filler with a longitudinal hole at one end, and in providing a wrapper whose end portion extends along a smooth curvature around the blunt end of the cigar and thence part-way into the hole, thereby lining the latter. This end portion of the wrapper forms an annular pocket within which the filler adjacent

to the smoking end of the cigar is compacted and held under all conditions.

A further feature of my invention lies in providing a cigar construction of the foregoing character wherein a reinforcement plug is removably associated with the smoking end of the cigar to seal the hole referred to and to engage the wrapper in a peculiarly efficient manner.

- 10 I achieve the foregoing objects and advantages, and such other objects and advantages as may hereinafter appear or be pointed out, in the manner illustratively exemplified in the accompanying drawing, wherein—
 15 Figure 1 is an enlarged elevational view, partly in section and partly broken away, to illustrate my present construction prior to the application of a plug of the present character;

- 20 Figure 2 is a similar view showing my completed construction as the cigar leaves the factory;

- 25 Figure 3 is a similar view, on a slightly reduced scale, showing the cigar as it may be smoked; and

Figure 4 is a view similar to the right end of Figure 2, illustrating a modification.

Referring particularly to Figure 3, I have shown a body of filler 10, which may be either 30 short or long, and which is substantially cylindrical throughout its entire length and un-tapered. In one end of this body, I provide a tapered longitudinal hole 11 which flares outwardly toward the end of the cigar and 35 whose walls are convexly shaped so as to merge along a smooth curvature with the blunt end of the body 10. A binder 12 is wrapped around the body 10 and terminates short of the blunt end thereof, and a wrapper 40 13 encircles the binder 12 and has an end portion 14 which extends around the blunt end along a smooth curvature and thence part-way into the hole 11, as indicated at 15. The 45 end portions 15 of the wrapper 13 serve as a lining for the outlet end of the opening 11, and also define an annular pocket 16 which surrounds the lining 15. This annular pocket is substantially U-shaped in cross-section and is adapted snugly and compactly to hold the 50 end portion of the filler body 10 in proper position.

The manner of constructing the cigar of Figure 3 is, of course, optional, but I prefer to proceed as illustrated in Figures 1 and 2. 55 In Figure 1, the filler body 10 has been encircled by the binder 12, and the wrapper 13 and the end portion 14 of the wrapper has been caused to envelop and overlie the entire rear blunt end of the body 10, being held in position by any suitable adhesive or the like, as is customary in the trade. Thereupon, a reinforcement plug 17 is inserted into the cigar construction. This plug may be of any suitable material, preferably unvarnished wood, 60 and its construction is of a peculiar and novel

character which provides a substantially circular head 18 and a tapered shank 19. The outer surface of the head 18 is gently convex, whereas the under surface of the head is gently concaved. The shank 19 is concavely 70 contoured so as to merge along a smooth and predetermined curvature with the concaved under surface of the head 18.

When the plug is applied it will assume the position of Figure 2, simultaneously providing the hole 11 previously mentioned and also engaging the wrapper end 14 to deflect the latter inwardly to form the pocket previously mentioned and to provide the lining 15. The particular shape of the plug results in a 80 stretching of the wrapper in a longitudinal direction whereby a greater length of draft opening is lined with wrapper than would be lined if no stretching took place. It will also be noted that the outer surface of the 85 head 18 forms a substantially smooth continuation of the wrapper at the rear end of the cigar where the wrapper merges along a gentle curvature with the marginal portion of the blunt end.

90 The mode of construction herein illustrated and described is particularly advantageous in connection with short filler cigars because the application of the plug 17 compresses and compacts the filler particles adjacent to the smoking end of the cigar, forcing them snugly and in compressed condition into the pocket 95 16 hereinbefore referred to.

The construction of Figure 2 illustrates the manner in which the cigar leaves the factory 100 and is packed and shipped, and it remains in this condition until the ultimate user purchases it. Regardless of the pressure to which the cigar may be subjected during packing or storage, and regardless of the relative 105 dryness of the cigar (which is likely to occur even under the most favorable conditions of care) cracking of the wrapper is practically prevented since the concaved under surface of the head 18 firmly engages and contacts 110 with the wrapper at all times and holds the same in the pocket-forming and hole-lining condition illustrated. I might mention that any attempt to apply a plug of the character 115 illustrated into the smoking end of any other type of cigar, as, for example, an open-ended cheroot, or any cigar having a tapered end, 120 would result almost immediately in splitting the cigar or in an ultimate cracking of the wrapper and splitting of the cigar construction as soon as the initial moisture content dries out. The present construction, however, has no such disadvantageous effects, and, quite to the contrary, produces an improved 125 firmness and staunchness at the outset, which is retained under all subsequent conditions, this being due to the manner in which the end portion of the wrapper is firmly engaged by the reinforcement plug and held in the positional relationship illustrated.

Obviously, the partially lined hole 11 constitutes a preformed draft opening for the cigar after the plug 17 is removed, such removal being readily accomplished by the ultimate user by merely inserting the nails of his thumb and forefinger underneath opposite portions of the head 18.

The cigar of Figure 3, when smoked, may be fully enjoyed without any annoyance whatever regardless of whether the filler is short or long and regardless of the moisture content or moisture absence of the construction. Not only will the wrapper remain intact throughout the entire process of smoking, but the filler, especially near and adjacent to the smoking end, will remain constantly in predetermined proper position.

In Figure 4, I have illustrated a slight modification in which the reinforcement plug has a head 20 with a blunted rim 21, and wherein the shank has a medial portion 22 which is substantially cylindrical. The body of the shank, however, is concaved, as shown at 23, this surface merging with the concave underneath surface of the head 20 for the purposes hereinbefore specified. The wrapper is held in predetermined position, as in Figure 2, and the construction is otherwise the same as Figure 2. The plug shape of Figure 4 may, under certain circumstances, be preferable to that of Figure 2, the cylindrical portion 22 serving to prevent undesired expulsion of the plug under the pressure of other cigars in a box, and the rim 21 facilitating the purpose-ful removal of the plug when the cigar is to be smoked.

Since the term "blunt end" signifies the burning end of a cigar, it will be understood that wherever this term has been used herein it is intended to designate the rear or smoking end. The shape of the burning end is entirely immaterial so far as the present invention is concerned.

It will be obvious that changes in the details herein described and illustrated for the purpose of explaining the nature of my invention may be made by those skilled in the art without departing from the spirit and scope of the invention as expressed in the appended claims. It is therefore intended that these details be interpreted as illustrative, and not in a limiting sense.

Having thus described my invention and illustrated its use, what I claim as new and desire to secure by Letters Patent is—

1. A blunt end cigar having in combination, a cylindrical body of short filler having an untapered blunt end and adapted to define the smoking end of the cigar, a binder around said body of filler and terminating substantially at the blunt end of the filler, a wrapper around said binder and blunt end, means defining an opening in said blunt end, a draft opening forming plug in said opening, said wrapper when stretched to surround the

blunt end constituting said draft opening defining means, the said wrapper being adapted to be stretched and forced into said opening by said plug, and forming a lining for the outer end portion of said opening, that portion of the filler adjacent the draft opening being compacted by said wrapper, and further compacted by the insertion of the plug.

2. The invention defined in claim 1 wherein in the plug comprises a blunt pointed shank and a head, there being a medial cylindrical shank portion adjacent the head.

3. A blunt end cigar having in combination, a cylindrical body of short filler having an untapered blunt end adapted to define the smoking end of the cigar, a binder around said body of filler and terminating substantially at the blunt end of the filler, a wrapper around said binder and blunt end, means defining a draft opening in said blunt end, a draft opening forming plug in said opening, said wrapper when stretched to surround the blunt end constituting said draft opening defining means, the said wrapper being adapted to be stretched and forced into said opening by said plug, the end of said wrapper defining said opening lying in a plane substantially coincident with the plane of the adjacent end of the binder, and forming a lining for the outer end portion of said opening, that portion of the filler adjacent said draft opening being compacted by said wrapper, and further compacted by the insertion of the plug.

In witness whereof, I have signed and sealed this specification this 2d day of May, 1931.

FREDERICK LANKERING.
